UNITED STATES PATENT OFFICE.

WILLIAM M. SAUNDERS, OF WATERBURY, CONNECTICUT, ASSIGNOR TO THE HOGE MANUFACTURING COMPANY, OF NEW YORK, N. Y., A CORPORATION OF NEW YORK.

PROPEL PENCIL.

Application filed June 18, 1922. Serial No. 569,310.

To all whom it may concern:

Be it known that I, WILLIAM M. SAUNDERS, a citizen of the United States, residing at Waterbury, county of New Haven, State of Connecticut, have invented a certain new and useful Improvement in Propel Pencils, of which the following is a full, clear, and exact description.

The present invention relates to propel pencils and has for its object to provide a novel and improved pencil of this character which is simple, cheap and durable in construction, and reliable and efficient in operation. It further has for its object to provide a new and improved propel pencil which can be readily assembled and disassembled.

The several features of the invention will be clearly understood from the following description and accompanying drawings, in which—

Fig. 1 is a side elevation, with the sheath shown partially in section and partially broken away, of a pencil embodying the features of the invention in their preferred form;

Fig. 2 is a longitudinal sectional view of the pencil taken on the line 2—2 of Fig. 1;

Figs. 3, 4, 5 and 6 are transverse sectional views, on an enlarged scale, taken on the lines 3—3, 4—4, 5—5 and 6—6 respectively, of Fig. 2; and

Fig. 7 is a detail side view of a friction spring shown in Figs. 2 and 5.

The pencil illustrated in the drawings is provided with a tip 4 and an operating knob 6 on opposite ends. The body of the pencil is surrounded by a removable sheath or casing 2 which forms merely a finishing shell.

The lower or tip end of the sheath is tapering, and the outer surface of the tip is correspondingly tapering so as to form a continuation of the outer tapering surface of the sheath. The tip 4 has a reduced portion 8 extending into the sheath and forming a shoulder 10 that abuts the end of the sheath.

This reduced portion 8 of the tip is screw-threaded into the lower end of a sleeve or bushing which is mounted in the sheath and has the outer surface of its forward end tapering to fit the tapering end of the sheath. The sleeve or bushing is made in two sections 14 and 16 that are screw-threaded together, the section 14 being provided with an internally threaded socket portion

18 which is screw-threaded on the lower end of the section 16 with the end of the socket abutting a shoulder 20 formed on the section 16. The outer wall of the socket portion 18 and the section 16 fit the sheath 2 so as to co-operate with the tapering end of the section 14 and the tip 4 to hold the sheath in position upon the sleeve 14—16. A spring arm 22 is arranged in a slot 24 in the section 14 and its free end is adapted to engage one of a series of slots 26 in the reduced screw-threaded portion of the tip 4 so as to form a detent holding the tip 4 from turning in the sleeve section 14. The spring arm 22 is secured to the sleeve by means of a ring 28 formed integral therewith which is clamped between the inner end of the sleeve section 16 and the inner end wall of the screw-threaded socket 18 in the sleeve section 14. The sleeve section 14 and the tip 4 are provided with axial bores that are continuations of each other. A lead guiding tube 30 extends through the axial bore in the sleeve section 14 and into the axial bore of the tip, the lower end of the tube being spaced a short distance from the end of the tip, and the wall of the bore in the tip below the tube being contracted to fit the lead. The lead guiding tube 30 is secured to the sleeve section 14 by a driving fit. The portion of the lead guiding tube extending upwardly beyond the bore of the sleeve section 14 extends into the sleeve section 16 and its end abuts against a nut 32 which is, preferably, separately formed and fixed by a drive fit in the sleeve section 16, the tube being in axial alinement with the screw-threaded bore of the nut. A lead follower or propeller 34 in the form of a screw is adapted to be screwed through the nut, and the upper end of the propeller is provided with a laterally projecting lug or tongue 36 that extends into a guide slot 37 in a tube 38 constituting a follower or propeller carrier, the slot extending from the upper end to near the lower end of the tube. The carrier 38 closely surrounds and guides the propeller 34, and its lower end is mounted for rotation in a removable cap 42 forming the upper end of the sleeve section 16. The mounting of the end of the propeller tube 38 in the sleeve section 16 comprises an outwardly turned flange 40 on the lower end of the tube that is held between the propeller nut 32 and a friction device 41 which

is held in position in the sleeve section 16 by a cap nut 42 screwed on the upper end of the sleeve section 16, the lower end of the propeller carrier 38 extending through 5 and being journaled in the upper end wall of the cap nut 42, so that the sleeve and carrier are connected together by a swivel joint containing a friction drag. The friction device 41 comprises two washers 43 and an annular 10 thrust spring 44 which is split and has its ends turned outwardly in opposite directions as shown in Figs. 5 and 7 and is interposed between the washers 43, the washers and spring surrounding the tube 38 and being 15 interposed between the flange on the tube and the upper end wall of the cap nut 42. This friction device 41 compensates for any looseness of parts between the propeller tube 38 and its mounting and places a slight 20 frictional drag on the propeller tube to prevent the tube from turning too freely.

A sleeve 54 is mounted on the tube 38 so as to close the propeller screw guiding slot 37, and is interposed between the cap nut 25 42 and the lower reduced end of an actuating member 45. The upper end of the sleeve 54 is provided with a slot 55 which is adapted to register with the guide slot 37 in the propeller tube 38, so that an instrument can 30 be inserted in the slot 37 to prevent its turning relative to the sleeve 54 when it is desired to apply or remove the member 45. Surrounding the sleeve 54 and spaced away therefrom is a tube 57, the ends of which fit 35 on bosses on the members 42 and 46, one at least of said fits being loose. The fit with part 42 is preferably a tight fit so as to prevent relative movement between 42 and 57. The space between the sleeve 54 and the 40 tube 57 serves as a magazine for the extra leads, access being had to the magazine for the purpose of replenishing or removing lead through openings 56 in the wall portion 58 of the actuating sleeve 46, these 45 openings being closed by the eraser plug 52 when in place.

The lower end of the actuating sleeve 45 which is reduced in diameter is screw-threaded on the upper end of the propeller tube 38. This actuating sleeve is provided 50 with portions 46 and 47 mounted to turn in the upper ends of the sheath 2 and tube 57 respectively, shoulders 50 and 51 that are adjacent to the upper ends of the sheath 2 and tube 57, and a portion extending beyond 55 the sheath that constitutes the operating knob 6, the peripheral surface of which is knurled or milled.

An eraser holding plug 52 fits within the 60 upper portion of the actuating sleeve 45 and its lower end portion is screw-threaded on the end of the propeller tube 38. With this construction the screw threads engaged by the eraser holder are made in the same operation as those engaging the sleeve 45 and

the screw threads in the bore of the plug 52 are made more easily than if made on the exterior of the holder. The upper portion of the eraser holding plug 52 extends beyond the end of the actuating sleeve 45 and its peripheral surface is knurled to enable the plug to be easily removed by unscrewing it from the propeller tube 38.

In the use of the pencil, the lead may be inserted in the lead guiding tube 30 either 75 by inserting it through the tip 4 while the tip is in place, or by removing the tip. In order to unscrew the tip 4 it is necessary when the sheath 2 is in place in the form shown, to press downwardly on the knob 6 80 or eraser plug 52 so as to keep the tapering end of the sleeve section 14 in binding engagement with the tapering end of the sheath 2 and thus overcome the holding action of the detent spring arm 22 on the tip. 85 Similarly, in screwing the tip into place it is necessary to press downwardly on the knob 6 or eraser plug 52 so as to cause the tapering end of the sleeve section 15 to bind on the tapering end of the sheath 2 and thus 90 overcome the holding action of the detent spring arm 22 on the tip. If, however, the tip 4 is turned without thus binding the sleeve 14—16 the spring arm 22 will cause the sleeve to turn with the tip and the tip 95 will not unscrew, which is advantageous as it obviates any danger of the tip being accidentally unscrewed or working loose so as to drop off.

It will be apparent that the lead propeller 100 may be advanced and retracted as desired by turning the knob 6. In order to permit the propeller to be disengaged from the nut 32 so as to prevent injury to the parts upon excessive retracting turning of the knob 105 6, and also in order to insure that the threads of the propeller and nut may be properly engaged after they have become disengaged, a yielding abutment is provided 110 which is engaged by the propeller near the end of its retracting movement and which, when the propeller is disengaged from the nut and the knob 6 is turned in the direction to advance the propeller, tends to urge the propeller to enter its nut 32. This yielding 115 abutment comprises a coiled spring 60 mounted in the propeller tube 38 and interposed between a plug 62 driven in the end of the tube 38 and a spacing pin 64 which is mounted to slide in the tube and is interposed between the spring 60 and the end of the propeller.

In order to prevent the lead from being jammed back into the nut 32 when the propeller has been retracted out of effective 125 engagement with the nut, a plunger 66 is mounted to slide in the lead guiding tube 30, which plunger has an enlarged head 68 on its rear or upper end of greater diameter than the bore of the nut, the plunger 66 130

serving as a lead engaging head for the propeller. The plunger is prevented from dropping out of the end of the tube and the extent of the advancing movement of the 5 plunger and the propeller is limited by the engagement of the head 68 thereof with the contracted lead engaging end of the tube 30. The lower end of the plunger by projecting through the tip indicates to the user when 10 the lead has been exhausted from the lead guiding tube 30.

From the foregoing it will be apparent that upon removing the tip 4, the sheath 2 can be removed, all of the remaining parts 15 of the pencil constituting a unit which when the tip is replaced constitutes an operative magazine prop pencil. When the sheath is removed, the remaining unit can be easily disassembled for the purpose of repairing 20 or renewing. To disassemble the parts, the eraser holding plug 52 may be unscrewed from the end of the propellar tube 38 and removed from the actuating sleeve 45, and then by inserting a suitable tool through 25 the slots 55 in the sleeve 54 and 59 in the tube 57 into the guide slot 37 in the propeller tube 38 to prevent the propeller tube from turning, the actuating sleeve 45 may be easily unscrewed and removed from the 30 propeller tube and the sleeve 54 slipped off of the propeller tube. The tube 38 is held in a similar manner when the actuating member 45 is being screwed thereon. By removing the cap nut 42 from the sleeve 35 section 16 the propeller tube 38 may be removed and, upon removing the plug 62 from the upper end of the tube 38, the propeller, spacing pin 64 and spring 60 slipped out of the tube, and if desired the cap nut 42 and 40 the friction device 41 may be slipped off of the propeller tube. The lead guiding tube 30 and the spring arm 22 may be removed by unscrewing their supporting sleeve section 14 from the sleeve section 16. 45 While it is preferred to employ the specific construction and arrangement of parts illustrated and described, it is to be understood that this construction and arrangement is not essential except so far as specified in 50 the claims, and may be changed or modified without departing from the broader features of the invention.

What I claim is:

1. A pencil of the class described having in combination a tubular sheath, a supporting sleeve removably mounted in the lower end portion of the sheath, a pencil tip screw-threaded into the lower end of the sleeve and constructed to hold the sleeve in 55 position, a screw-threaded lead propeller extending into said sleeve for advancing the lead through the tip of the pencil, a tube into which said propeller extends having its lower end mounted for rotation with relation to the sleeve, a nut carried by said 60

supporting sleeve and engaging said propeller, a knob rotatably mounted in the upper end of the sheath and secured to the tube for rotating the tube, and means comprising connections between the tube and propeller for rotating the propeller upon rotation of the tube, said supporting sleeve, tube, propeller and knob capable of being removed from the sheath as a unit upon removing said pencil tip. 70

2. A pencil of the class described having in combination a tubular sheath, a supporting sleeve removably mounted in the lower end portion of the sheath, a pencil tip screw-threaded into the lower end of the sleeve and constructed to hold the sleeve in position, a screw-threaded lead propeller extending into said sleeve for advancing the lead through the tip of the pencil, a tube into which said propeller extends having its lower end mounted for rotation with relation to the sleeve, a nut carried by said supporting sleeve and engaging said propeller, a knob rotatably mounted in the upper end of the casing and secured to the tube for 80 rotating the tube, and means comprising connections between the tube and propeller for rotating the propeller upon rotation of the tube, said supporting sleeve, tube, propeller and knob capable of being removed from the sheath as a unit upon removing said pencil tip, a magazine tube within said sheath spaced away from said first mentioned tube, the space between said first mentioned tube and magazine tube being 85 closed by said knob. 90

3. A pencil of the class described having in combination a tubular sheath, a nut held in fixed position with relation to the sheath, an elongated tube rotatably mounted 105 in the sheath, a lead propeller screw-threaded through the nut and extending into said tube, said propeller and tube having a tongue and slot connection between them for causing the propeller to rotate with the tube and permitting axial movement of the propeller with relation to the tube, and an operating knob located at the upper end of the sheath and secured to the tube, and a spring exerting a drag on said elongated 110 tube. 115

4. In a propel pencil, the combination of a sheath having in its lower end a sleeve, a slotted follower carrier connected thereto by a swivel joint and extending toward the 120 upper end of said sheath, operating means secured to the upper end of said carrier, a threaded follower within said carrier and engaging the slot therein, a nut within said sleeve adapted to engage the lower end of 125 said follower and a spring friction device at said swivel joint and producing a drag upon said follower carrier relatively to said sleeve.

5. In a propel pencil, the combination of 130

5 a sheath having in its lower end a sleeve, a slotted follower carrier connected thereto by a swivel joint and extending toward the upper end of said sheath, a threaded follower within said carrier and engaging the slot therein, a nut within said sleeve adapted to engage the lower end of said follower and a spring friction device producing a drag upon said follower carrier relatively to said sleeve, 10 said sleeve having at its upper end a cap screw-threaded thereon and containing said drag producing means.

6. In a propel pencil, the combination of a sheath having in its lower end a sleeve, a slotted follower carrier rotatable relatively thereto, and extending toward the upper end of said sheath, a threaded follower within said carrier and engaging the slot therein, a nut within said sleeve adapted to engage the lower end of said follower, a yielding abutment within the upper end of said follower carrier for forcing said follower toward said nut when fully retracted.

7. In a propel pencil, the combination of a sheath having in its lower end a sleeve, a slotted follower carrier rotatable relatively thereto and extending toward the upper end of said sheath, a threaded follower within said carrier and engaging the slot therein, a nut within said sleeve adapted to engage the lower end of said follower, a yielding abutment within the upper end of said follower carrier for forcing said follower toward said nut when fully retracted, said yielding abutment comprising a spring and a movable spacing pin located between the upper end of said follower and said spring.

8. In a propel pencil, the combination of a sheath, a sleeve held in its lower end, a slotted follower carrier swiveled to said sleeve so as to be held from longitudinal movement and so as to be rotatable relatively thereto and extending toward the upper end of said sheath, a threaded follower within said carrier and engaging the slot therein, a nut within said sleeve adapted to engage the lower end of said follower, the upper end of said follower carrier being screw-threaded and an operating member having a screw-threaded bore and making engagement with the screw-threaded upper end of said carrier, said operating member having a shoulder directly engaging the upper end of said sheath.

55 9. In a propel pencil, the combination of a sheath having in its lower end a sleeve, a slotted follower carrier rotatable relatively thereto and extending toward the upper end of said sheath, a threaded follower within said carrier and engaging the slot therein, a nut within said sleeve adapted to engage the lower end of said follower, the upper end of said follower carrier being screw-threaded, an operating member having a screw-threaded bore and making engagement with the

70 screw-threaded end of said carrier, said operating member having a recess into which the screw-threaded end of said carrier protrudes and an eraser carrier entering said recess and screw-threaded upon said protruding end of said carrier.

10. In a pencil, the combination of a tip having a screw-threaded projecting upper portion, a body portion having a screw-threaded recess with which said screw-threaded projection engages and a spring detent fixed relatively to one of said two members and acting to hold said tip against being accidentally unscrewed from said body portion.

11. In a propel pencil, the combination of a sheath having in its lower end a sleeve, a removable tip having a screw-threaded extension screwed into the lower end of said sleeve and a shoulder abutting the end of 85 said sheath, the upper end of said screw-threaded projection having a recess, a spring detent carried by said sleeve and adapted to engage said recess.

12. In a propel pencil, the combination of 90 a sheath having in its lower end a sleeve, a removable tip having a screw-threaded extension screwed into the lower end of said sleeve and a shoulder abutting the end of said sheath, the upper end of said screw-threaded projection having a recess, a spring detent carried by said sleeve and engaging said recess, said spring having a transverse portion and said sleeve having two screw-threaded portions clamping said transverse 100 portion between them.

13. In a propel pencil, the combination of a sheath having in its lower end a sleeve, a slotted follower carrier swiveled thereto so as to be rotatable relatively and extending toward the upper end of said casing, an operating member on the upper end of said carrier, a threaded follower within said carrier and engaging the slot in said carrier, a nut within said sleeve adapted to engage the lower end of said follower, a removable tip having a screw-threaded extension screwed into the lower end of said sleeve and a shoulder abutting the end of said sheath, 105 said sleeve and follower carrier being removable as a unit through the upper end of said sheath when said tip is removed.

14. In a propel pencil, the combination of a sheath, a sleeve in its lower end, a slotted follower carrier swiveled and rotatable relative to said sleeve and extending toward the upper end of said sheath, a threaded follower within said carrier and engaging the slot therein, a nut within said sleeve adapted to engage the lower end of said follower, an operating member secured to the upper end of said follower carrier and a second sleeve surrounding said follower carrier and extending substantially from said operating member to said first sleeve, 120 125 130

a magazine tube within said sheath and spaced from said carrier to form a magazine, and a closure for said magazine connected to said carrier.

5 15. In a propel pencil, the combination of a sheath having in its lower end a sleeve, a slotted follower carrier swiveled and rotatable relative thereto, and extending toward the upper end of said sheath, a thread-

10 ed follower within said carrier and engaging the slot therein, a nut within said sleeve adapted to engage the lower end of said follower, an operating member secured to the upper end of said follower carrier and

15 a sleeve surrounding said follower carrier and extending substantially from said operating member to said first sleeve, said second sleeve having an opening adapted to register with an opening in said follower

20 carrier and to permit the insertion of a tool to prevent relative rotation of said second sleeve and said follower carrier.

16. In a propel pencil, the combination of a sleeve carrying at its upper end a nut 25 having a screw-threaded bore, a screw-threaded follower adapted to enter said bore and to be retracted therefrom, means for rotating said screw-threaded follower, a lead guide below said screw-threaded bore 30 and a plunger within said lead guide adapted to be engaged by the upper end of a lead therein, and protect said bore from said lead.

17. In a propel pencil, the combination of 35 a sleeve carrying at its upper end a nut having a screwthreaded bore, a screw-threaded follower adapted to enter said bore and to be retracted therefrom, means for rotating said screw-threaded follower, a lead guide below said screw-threaded bore 40 and a plunger within said lead guide adapted to be engaged by the upper end of a lead therein, said plunger having a reduced portion adapted to protrude from the end of 45 the pencil when said plunger is in its lowest position.

18. In a propel pencil, a sleeve member, a screw-threaded follower, a tube member con-

taining said follower and secured to said sleeve member by a swivel connection, one 50 of said swiveled members having a screw-thread engaged by said follower, and the other having means for preventing relative movement between it and said follower and permitting longitudinal movement of said follower when said tube member is turned relatively to said sleeve member, a sheath 55 surrounding said parts and removably fixed relatively to said sleeve member.

19. In a propel pencil, a sleeve member, a screw-threaded follower, a tube member containing said follower and secured to said sleeve member by a swivel connection, one 60 of said swiveled members having a screw-thread engaged by said follower, and the other having means for preventing relative 65 movement between it and said follower and permitting longitudinal movement of said follower when said tube member is turned relatively to said sleeve member, a sheath 70 surrounding said parts, and a tip secured to said sleeve member and abutting against the lower end of said sheath and holding the sheath upon said other parts.

20. In a propel pencil, a sleeve member, a screw-threaded follower, a tube member containing said follower and secured to said sleeve member by a swivel connection, one 75 of said swiveled members having a screw-thread engaged by said follower, and the other having means for preventing relative 80 movement between it and said follower and permitting longitudinal movement of said follower when said tube member is turned relatively to said sleeve member, a sheath 85 surrounding said parts and fixed relatively to said sleeve member, a tip secured to said sleeve member and abutting against the lower end of said sheath and holding the sheath upon said other parts, a tube located 90 within said sheath and spaced away from said tube member so as to form a magazine, and removable means for closing the upper end of said magazine.

WILLIAM M. SAUNDERS.
